COMBINED COASTER AND CARD HOLDER

John D. Milne, Toronto, Ontario, Canada (25 Bridesbury Drive, Apt. 208, Weston, Ontario, Canada)

Filed Nov. 26, 1963, Ser. No. 77,564

Term of patent 14 years

(Cl. D44—10)

FIG. 1 is a perspective view of the combined coaster and card holder showing my new design;

FIG. 2 is a plan view of the underside thereof;

FIG. 3 is a side elevational view thereof;

FIG. 4 is an end view thereof; and

FIG. 5 is a diagonal sectional view on the plane of line 5—5 of FIG. 2.

I claim.

The ornamental design for a combined coaster and card holder, as shown.
